UNITED STATES PATENT OFFICE.

LEONARD C. FARRAR, OF NEW YORK, N. Y.

SAFETY CATCH FOR BROOCHES, EMBLEMS, ETC.

Application filed August 3, 1928. Serial No. 297,130.

This invention relates to improvements in fastening means for brooches, fraternity emblems and for other purposes and has for its principal objects the provision of a simple, 5 cheap and effective device which is positive in its action and attractive in appearance.

In the accompanying drawings in which I have illustrated a brooch embodying my invention

- 10 Figure 1 is a plan view;
Fig. 2 is a vertical section on the line 2—2 of Fig. 1;
Fig. 3 is a plan view showing the pin in a locked position; and
15 Fig. 4 is a vertical section on the line 4—4 of Fig. 3.

Referring to the drawings and the construction shown therein, the reference numeral 1 designates a split ring which may be ornamented in any desired manner and is provided 20 with knobs or ornamental end pieces 2, 2' which normally are adapted to have elastic engagement with each other as a result of the natural elasticity of the metal of which such 25 split ring is constructed. A sleeve 3 is slidably mounted on said ring and is provided with a metal pin 4 that is adapted to project outwardly therefrom and is of a sufficient length to completely span said ring.

- 30 In order to fasten said brooch to a garment, such as *y*, while the same is lying in a plane below the plane of the split ring 1, the point *b* of said stick pin, is first inserted through the garment at the point *c*, is passed beneath 35 the same to a sufficient distance so as to permit of a firm anchorage being obtained and then is caused to pass through the same at a point such as *d*. Having caused the stick pin to pass through the garment as above stated, 40 and while the split ring is held in the position shown in Fig. 1, the point *b* of the pin member is caused to pass upwardly between said knobs 2, 2' and thereupon the split ring 1 is rotated through a partial revolution so as 45 to bring the point *b* above the split ring at a point intermediate the ends thereof, as shown in Fig. 3 and thereby the point of said stick pin is positively held in such a position that it projects into a plane above the plane of the 50 split ring 1. In this latter position, as is evident, the knob 2 will prevent the stick pin from becoming released and it is only by intentional movement of the split ring to the 55 position shown in Fig. 1 that the point *b* can escape between the two knobs 2, 2' and be re-

stored to a position that will permit of the same slipping out of the fabric or other material to which the brooch or pin is secured.

While this invention has been illustrated as applied to a brooch, it is obvious that a 60 fraternity pin or emblem or other device may be equipped therewith, for example, in applying the same to a fraternity pin, the shell or base on which the inscription is displayed is rigidly secured preferably to the ring 1 and 65 the sleeve 3 is slidable with respect to such shell. The method of attaching said fraternity pin would therefore be similar to the method above described with respect to the attachment of a brooch to a garment. 70

Among the advantages of my improved safety catch or pin are the facts that it lends itself for use on a wide variety of articles, it is extremely simple and cheap to construct and is remarkably positive and effective in 75 its action besides being attractive in appearance. Furthermore, it is sturdy and not liable to become bent or inoperative.

Obviously, if desired, a suitable safety sheath or tip can be fitted over the end *b* of the 80 stick pin and various other modifications within the scope of the appended claims may be made without departing from the spirit of my invention.

Having thus described my invention, what 85 I claim is:

1. In a clasp pin, the combination comprising a discontinuous skeleton frame, a swinging pin member slidably mounted thereon and means on the respective terminals of said 90 support for preventing the accidental displacement of said pin from the support when the portion of the pin intermediate its ends is in engagement with a flexible support and the end of said pin is under tension and resting 95 on said ring.

2. In a clasp-pin, the combination comprising a split ring, a sleeve slidably and rotatably mounted thereon, a pin member secured to said sleeve and of a sufficient length to span 100 said ring and bosses on the adjacent ends of said split ring for preventing accidental escape of the end of the pin member between the ends of the split ring when the pin is secured to a flexible supporting surface and is resting 105 under tension on said split ring.

Signed at New York, in the county and State of New York, this 31st day of July, 1928.

LEONARD C. FARRAR.
